PROCESS FOR LIGHT NAPHTHA UPGRADING

Donald D. MacLaren, Scotch Plains, N.J., assignor to
Esso Research and Engineering Company, a corpora-
tion of Delaware

Application March 1, 1957, Serial No. 643,343

8 Claims. (Cl. 208—138)

The present invention relates to the hydroforming of hydrocarbons and particularly to an improved method for upgrading light naphtha fractions to produce high octane number motor fuels in high yields. More particularly, it relates to obtaining a maximum yield octane relation when processing light naphthas boiling in the range of about C₅/200° F. by using process conditions to obtain maximum aromatics yield by operating at only enough severity to give just 100% C₇ conversion thus minimizing C₈ conversion. Chromatographic analysis of the feed and of the hydroformate may be used to select these process conditions. The hydroformate is then processed to separate out the small amount of n-C₅ and C₆ paraffins which have low octane rating. These are recycled to the reaction zone or are used in high quality jet fuels or other specialty products. By this process a 19 to 23% increase in yield (over conventional platinum hydroforming) of C₅+ motor fuel material at 100 octane level is obtained.

Hydroforming is a well known and widely used process for upgrading hydrocarbon fractions boiling in the motor gasoline or naphtha boiling range to increase their octane numbers and to improve their burning or engine cleanliness characteristics. In hydroforming, the hydrocarbon fraction or naphtha is contacted at elevated temperatures and pressures and in the presence of hydrogen or hydrogen enriched process gas with solid catalytic materials under conditions such that there is no net consumption of hydrogen and ordinarily there is a net production of hydrogen in the process. A variety of reactions occur during hydroforming, including dehydrogenation of naphthenes to the corresponding aromatics, hydrocracking of paraffins, isomerization of straight chain paraffins to form branch chain paraffins, dehydrocyclization of paraffins and isomerization of compounds such as ethylcyclopentane to form methylcyclohexane which is readily converted to toluene. In addition to these reactions, some hydrogenation of olefins and polyolefins occur and sulfur or sulfur compounds are eliminated by conversion to hydrogen sulfide or to catalytic metal sulfides making the hydroformate burn cleaner or form less engine deposits when used as the fuel in an internal combustion engine.

Hydroforming operations are ordinarily carried out at temperatures of 750°–1150° F. in the pressure range of about 50 to 1000 pounds per square inch and in contact with such catalysts as molybdenum oxide, chromium oxide, or in general, oxides or sulfides of metals of groups IV, V, VI, VII and VIII of the periodic system of elements alone, or generally supported on a base or spacing agent such as alumina gel, precipitated alumina or zinc aluminate spinel. A good non-precious metal hydroforming catalyst is one containing about 10 wt. percent molybdenum oxide upon an aluminum oxide base prepared by heat treating a hydrated aluminum oxide or upon a zinc aluminate spinel. A good precious metal hydroforming catalyst is one employing an alcohohalate (eta) alumina base carrying 0.6% by weight of platinum. Catalysts of lower platinum content may also be used as may also silica stabilized alumina base catalysts.

2

It has been proposed in U.S. Pat. 2,689,823, September 21, 1954, to effect the hydroforming of naphtha fractions in the presence of a dense fluidized catalyst mass in a fluidized solids reactor system in which naphtha vapors are passed continuously through the dense fluidized bed of hydroforming catalyst particles in a reaction zone, spent catalyst particles being withdrawn from the dense bed in the reaction zone and passed to a separate regeneration zone where inactivating carbonaceous deposits are removed by combustion, whereupon the regenerated catalyst particles are returned to the main reactor vessel. Fixed bed hydroforming, of course, is conducted by passing the naphtha vapors through a fixed bed of catalyst and if regeneration is required, shutting down the particular reactor, purging to remove reactant vapors, withdrawing the catalyst or regenerating by passing an oxygen-containing gas through such catalyst bed.

Hydroforming is usually applied to a rather wide boiling range naphtha, i.e. to one having a boiling range of from about 125° F. to about 400°–430° F. It has been known that the lower boiling naphthas are not substantially improved by hydroforming processes as ordinarily conducted. The extensive report entitled "An Appraisal of Catalytic Reforming" in Petroleum Processing for August 1955, for example, states at page 1174: "Optimum reformer utilization is obtained by not using feed stock constituents boiling much below 200° F. which do not contribute greatly to increased octane during reforming as these merely take up reformer capacity better used for high boiling materials more suitable to octane upgrading." In view of the continuing demand for more and higher octane number gasolines, however, it is becoming increasingly important to upgrade these lower boiling naphtha fractions.

It is the object of this invention to provide the art with an improved method for hydroforming or upgrading light naphthas.

It is also the object of this invention to provide a simple, effective method for upgrading light naphthas boiling in the range of from about 100°–200° F., preferably from about 100°–180° F. to form high octane products in high yields.

These and other objects will appear more clearly in the detailed specification and claims which follow and in the accompanying system designed to carry out the present invention and in which Figures 2–6 present an analysis of chromatographic data obtained on a C₆–200° F. cut light naphtha processed by platinum hydroforming at pressures in the range of 50–300 pounds.

From this data it has now been found that there is an optimum conversion level to which hydroforming should be carried. Above this conversion level aromatics are destroyed and high octane iso C₈'s are cracked away. The accompanying Figures 2 and 3 illustrate this destruction of aromatics occurring above the optimum octane level of about 95 octane, and that a maximum yield of aromatics occurs at that level.

Accompanying Figure 4 shows that this maximum occurs at the point where complete conversion of the C₇ paraffins has just been reached, Figure 5 shows that this corresponds to about 75–80% conversion of the C₈ paraffins and Figure 6 shows that if severity is increased further, C₅ paraffins, especially iso C₅'s are cracked away reducing high octane gasoline yield. Thus it can be seen from these figures taken together that for platinum hydroforming optimum conversion is obtained at just 100% conversion of C₇ paraffins which corresponds to 75–80% conversion of C₈ paraffins. This is the point of maximum aromatic and total gasoline yields. It is seen that above this level further octane improvement is obtained only by cracking away the remaining C₈ paraffins and at the same time destroying C₅ paraffins and some

of the aromatics already in the product. Cracking of the C₅'s is doubly disadvantageous in that the iso C₅ paraffins are preferentially cracked.

According to the present invention it is proposed to take advantage of this optimum conversion by separating out from the product the nC₅ and C₆ paraffins. These may then be recycled to the hydroforming conversion zone or separately used as a component in high quality jet fuel or other specialty products. By this invention large improvements in yield of 100+ clear octane number motor fuels of the order of a 20% increase are obtained.

The advantages of this invention may of course be carried out in either fixed or fluid bed platinum hydroforming. In addition, however, fluid molybdenum oxide catalyst hydroforming is also susceptible to the method of this invention. Thus similar chromatographic data under varying process conditions from fluid molybdenum oxide hydroforming would be obtained and reaction conditions would then be chosen so that conversion would be carried to the point of just 100% C₇ conversion.

The invention of this application will be more clearly understood by reference to Figure 1 which diagrammatically represents a system adapted to carry out the present invention.

Referring to this drawing, a C₅-200 cut light naphtha is supplied through line 1 past closed valve 2, through open valve 3 to distillation column 4. This column is operated to separate out a 180°-200° F. bottoms fraction which is passed through line 5 to separate heavy naphtha hydroforming equipment not shown in which it may be more advantageously processed. From the top of column 4 the C₅-800° F. cut fraction is fed through line 6 to the light naphtha hydroformer 8. Alternatively, if desired, the entire C₅-200° F. light naphtha may be fed directly to the light naphtha hydroformer 8 by closing valve 3 and opening valve 2 in line 7. Conditions are set in the hydroformer to obtain maximum aromatics conversion and 100% conversion of C₇ paraffins both with the minimum conversion of C₆ paraffins. From hydroformer 8, product is passed through line 9 to suitable catalyst recovery equipment, if desired, or necessary, and is then passed through suitable heat exchanger and condenser equipment to gas liquid separator 10 wherein recycle gas is separated and passed through line 11 to compressor 12. From compressor 12 gas is recycled through line 13 back to the hydroformer. From separator 10 the liquid hydroformate is passed to stabilizer 15 wherein the C₄- material is removed overhead through line 16 and is passed to conventional light ends recovery processing not shown. The bottoms from stabilizer 15 are fed through line 17 to deisopentanizer column 18. Isopentane is withdrawn from the top of this column through line 19 as one of the major products and the bottoms are passed through line 20 to superfractionator column 21. From the bottom of this superfractionator column benzene (or if the full C₅-200° F. feed was hydroformed then benzene and aromatics) are passed through line 22 as a major product of the process to blending facilities not shown for use with the isopentane in high octane motor fuels. From the top of the superfractionator 21 normal C₅ and C₆ paraffins are passed through line 23 past closed valve 24 through open valve 26 and line 27 back to line 6 for recycle to the hydroformer. Alternatively, if desired, valve 26 may be closed and these nC₅ and C₆ paraffins may be passed through open valve 24 and line 25 from the system and used advantageously as a component in high quality jet fuel or other specialty products. The main products from operation as proposed by this invention are isopentane and aromatics both of which have leaded octane numbers well over 100.

By following the teachings of this application the maximum yield of isopentane and aromatics possible in light

naphtha hydroforming will be obtained. For example, if it is desired, to make 100.5 clear octane from a C₅/180° F. Arabian feed by conventional once-through operation in 300 pound platinum hydroforming a yield of 34.5% C₅+ material only is attainable. By the present invention, on the other hand, where the platinum hydroformer is operated at the optimum conversion of C₆ paraffins with recycle of nC₅ and C₆ paraffins, an overall yield of 42.5% for the same octane number is attained. This is a gain of 8% on fresh feed in yield or based on such ordinary yield from conventional hydroforming an improvement in yield of 23%. At the same time the catalyst required in the hydroformer is greatly reduced; a feed rate of 1.0 wt. of feed/hr./wt. of catalyst being required by the conventional process and a feed rate of 1.7 wt. of feed/hr./wt. of catalyst being possible by the present process. This latter is very significant in view of the extremely high cost of the platinum catalyst used in platinum hydroforming.

Alternatively in processing a C₅-200° F. Arabian feed to 101.5 Research clear octane number conventionally by platinum hydroforming, a C₅+ yield of 31% is obtained. By the method of this application with separation out of the nC₅ and C₆ paraffin for use in other products a yield of 37% for the same 101.5 octane is obtained. This is an increase in yield of C₅+ of 6% on fresh feed or an improvement in yield of 19%. In addition again platinum catalyst requirements for the process are greatly reduced, i.e. 0.9 wt. feed/hr./wt. of catalyst feed rate for conventional hydroforming and 2 wt. feed/hr./wt. of catalyst feed rate for the present process.

The following example is illustrative of the present invention:

Example

A C₅/200° F. light naphtha Arabian feed having an API gravity of 71.9 and a Research clear octane number of 59 is fed to a light naphtha fixed bed platinum hydroformer operating at 950° F. and 300 p.s.i.g. The platinum alumina catalyst contains 0.6% platinum on high surface area eta alumina derived from aluminum alcoholate and is in the form of $\frac{1}{16}$ " x $\frac{3}{32}$ " pills of a density of 47 pounds/c.f. Recycle gas is supplied to the reactor at a rate of 3000 cubic feet per barrel of oil and the space velocity of the oil is 2.0 pounds of oil per hour per pound of catalyst in the reactor.

Stabilizer 15 is operated to remove the C₄- material and deisopentanizer 18 is operated to separate overhead the isopentane main product of the process. Superfractionator 21 then separates the nC₅ and C₆ paraffin material overhead for use in other products leaving as bottoms the benzene, the other main product from the process. The isopentane and benzene fractions are then mixed to obtain a 37.0% (based on feed) yield of C₅+ material of 101.5 Research clear octane number.

It is to be understood that this invention is not limited to the specific example above which has been offered merely as an illustration and that modifications may be made without departing from the spirit of this invention.

What is claimed is:

1. A method for upgrading light naphtha fractions boiling in the range of about C₅/200° F. which comprises hydroforming such feed at conditions of severity to obtain just 100% C₇ normal and isoparaffin conversion, thereby minimizing C₆ normal and isoparaffin conversion of about 75 to 80% and attaining maximum aromatic yield; stabilizing such hydroformate to remove C₄ and lighter material; fractionating to separate high octane isopentane product overhead leaving nC₅ and C₆ paraffins with benzene in bottoms of a column; superfractionating the bottoms from such column to obtain high octane benzene product as bottoms and an nC₅ and C₆ paraffins fraction overhead suitable for use in high quality jet fuels or other specialty products, this nC₅ and C₆

paraffins fraction being only a small amount of the total product.

2. The process as in claim 1 in which the catalyst used in hydroforming is platinum on high surface area alumina.

3. A method for upgrading light naphtha fractions boiling in the range of about C₅/200° F. which comprises hydroforming such feed at conditions of severity to obtain just 100% C₇ normal and isoparaffin conversion, thereby minimizing C₆ normal and isoparaffin conversion of about 75 to 80% and attaining maximum aromatic yield; stabilizing such hydroformate to remove C₄ and lighter material; fractionating to separate high octane isopentane product overhead leaving nC₅ and C₆ paraffins with benzene in bottoms of a column; superfractionating the bottoms from such column to obtain high octane benzene product as bottoms and an nC₅ and C₆ paraffins fraction overhead and recycling such nC₅ and C₆ paraffins fraction to the hydroforming conversion zone.

4. The process as in claim 3 in which the catalyst used in hydroforming is platinum on high surface area alumina.

5. A method for upgrading light naphtha fractions boiling in the range of about C₅/180° F. which comprises hydroforming such feed under conditions of only enough severity to obtain just 100% C₇ normal and isoparaffin conversion thereby minimizing C₆ normal and isoparaffin conversion of about 75 to 80% and attaining maximum aromatic yield; stabilizing such hydroformate to remove C₄ and lighter material; fractionating to separate high octane isopentane product overhead leaving nC₅ and C₆ paraffins with benzene in bottoms of a column; superfractionating the bottoms from such

column to obtain high octane benzene product as bottoms and an nC₅ and C₆ paraffins fraction overhead and recycling such nC₅ and C₆ paraffin fraction to the hydroforming conversion zone.

5. The process as in claim 5 in which the catalyst used in hydroforming is platinum on high surface area alumina.

7. A method for upgrading light naphtha fractions boiling in the range of about C₅/180° F. which comprises hydroforming such feed under conditions of only enough severity to obtain just 100% C₇ normal and isoparaffin conversion thereby minimizing C₆ normal and isoparaffin conversion of about 75 to 80% and attaining maximum aromatic yield; stabilizing such hydroformate to remove C₄ and lighter material; fractionating to separate high octane isopentane product overhead leaving nC₅ and C₆ paraffins with benzene in bottoms of a column; superfractionating the bottoms from such column to obtain high octane benzene product as bottoms and an nC₅ and C₆ paraffins fraction overhead suitable for use in high quality jet fuels or other specialty products, this nC₅ and C₆ paraffin fraction being only a small amount of the total product.

8. The process as in claim 7 in which the catalyst used in hydroforming is platinum on high surface area alumina.
